UNITED STATES PATENT OFFICE.

HENDRIK CHRISTIAAN ROOS, OF GRAND RAPIDS, MICHIGAN.

EMBOSSING-MACHINE.

1,142,273.

Specification of Letters Patent. Patented June 8, 1915.

Application filed April 17, 1914. Serial No. 832,608.

To all whom it may concern:

Be it known that I, HENDRIK CHRISTIAAN Roos, a citizen of the Netherlands, residing at Grand Rapids, in the county of Kent 5 and State of Michigan, have invented new and useful Improvements in Embossing-Machines, of which the following is a specification.

The invention relates to an improvement 10 in embossing machines, and particularly to a construction of die receiving plate, whereby scoring rules may be adjustably incorporated therewith to insure the embossing and scoring at the single operation.

15 The main object of the present invention is the provision of an embossing machine wherein the bed plate is provided with appropriately formed recesses to which the scoring rules may be adjustably secured for 20 simultaneous action, with the embossing plate whereby book covers for example may be scored and embossed at a single operation.

The invention in the preferred form of 25 details will be described in the following specification, reference being had particularly to the accompanying drawings, in which:—

Figure 1 is a perspective view illustrating 30 the improved bed plate, showing the embossing die and scoring rules in place thereon. Fig. 2 is a sectional view taken through one of the slots of the bed plate.

In carrying out the improvement, I provide bed plate 1 on which the embossing die 35 2 is secured in any usual or preferred manner with a series of parallel slots 3. These slots open through the upper surface of the plate 1 in the form of narrow rectangular openings, the lower portions of the slots 40 being laterally extended so that they open through the bottom of the plate in increased transverse dimensions, as at 4. The slots thus present a T-form in cross section.

With the embossing die secured to the bed 45 plate in the usual manner, I contemplate affixing scoring rules 5, one or more as may be necessary to such bed plate through the medium of bolts 6 having heads 7 provided with the usual kerf, the bolts passing 50 through the scoring rules with the head fitting below the operative edges of the rules

and between them as illustrated. The threaded end of the bolt engages a nut 8 seating in the head portion of the slot.

The scoring rules are arranged transversely of the slots, that is each rule extends over all of the employed slots and is preferably secured in the manner described in each.

The slots 3 are of such length as to accommodate a plurality of rules if desired, or to permit the coöperation of one rule and its adjustment with relation to the adjacent die as may be desired to properly locate the scoring rules.

In use, by the proper positioning of one or more of the scoring rules as may be necessary, the book cover or the like being embossed may be simultaneously scored for folding, thereby determining at a single operation what has previously required two. It is of course understood that the bed plate may be provided with slots 3 at different points in order to provide for any desired location of the scoring rules, the arrangement of the slots being not material in the present invention.

While I have shown and described the slots as arranged for horizontal adjustment of the scoring rules, it is obvious that they may, within the spirit of the invention be arranged for vertical adjustment when the rules are so used, and I do not deem it necessary to illustrate this detail, as it is obvious.

What is claimed is:—

1. A bed plate for embossing machines formed with a plurality of parallel slots having head enlargements and a pair of scoring rules lying in parallelism and having relative adjustment, each of said rules having its face formed with a pair of parallel scoring edges, bolts passing through said rules and slots, and ends coöoperating with the bolts and seated in the headed enlargements for securing said rules in any of their adjustments.

2. A bed plate for embossing machines formed with a plurality of parallel slots having head enlargements and a pair of scoring rules lying in parallelism and having relative adjustment, each of said rules having one face centrally depressed through-

out the length thereof so as to form a pair of spaced scoring edges, bolts passing through said rules and slots, and ends co-operating with the bolts and seated in the headed enlargements for securing said rules in any of their adjustments.

In testimony whereof I affix my signature in presence of two witnesses.

HENDRIK CHRISTIAAN ROOS.
